(12) **United States Design Patent**
Kaffash

(10) **Patent No.:** **US D674,523 S**
(45) **Date of Patent:** **** Jan. 15, 2013**

(54) **LED SURFACE MOUNT AND VEHICLE LIGHT**

D653,370 S * 1/2012 Grebert et al. D26/28

* cited by examiner

(76) Inventor: **Modjgan Kaffash**, Great Neck, NY
(US)

Primary Examiner — Marcus Jackson
(74) *Attorney, Agent, or Firm* — Michael D. Eisenberg

(**) Term: **14 Years**

(57) **CLAIM**
The ornamental design for a LED surface mount and vehicle light, as shown and described.

(21) Appl. No.: **29/383,145**

DESCRIPTION

(22) Filed: **Jan. 12, 2011**

FIG. 1 is a perspective view of a LED surface mount and vehicle light showing my new design;

(51) **LOC (9) Cl.** **26-06**

FIG. 2 is a left side view of the surface mount and vehicle light;

(52) **U.S. Cl.** **D26/28**; D26/1

FIG. 3 is a top view of the surface mount and vehicle light;

(58) **Field of Classification Search** D26/1,

FIG. 4 is a right side view of the surface mount and vehicle light;

D26/28-36; 362/459-468, 475-478, 485-487;

FIG. 5 is a front view of the surface mount and vehicle light;

313/313, 315, 316, 317, 318, 493

FIG. 6 is a rear view of the surface mount and vehicle light;

See application file for complete search history.

and,

(56) **References Cited**

FIG. 7 is a bottom view of the surface mount and vehicle light.

U.S. PATENT DOCUMENTS

The diameter of the circular pattern formed by the LEDs from center to center of opposing LEDs can range from 0.5 inches to 3 inches.
